TRAVELING BAG

Abraham Levine, Elizabeth, N. J., assignor to
Presto Lock Corporation, a corporation of New
York

Application December 17, 1934, Serial No. 757,743

3 Claims. (Cl. 312—178)

This invention relates to traveling bags of the wardrobe type; and more particularly to the provision of means in such bags to enable the transportation of clothing without rumpling or disarrangement.

It is desirable that luggage be as light in weight as practicable, and for this reason there have been produced various types of hand luggage and "over night" bags. However, due to the restricted size of such luggage, dresses and suits of men's clothing can not be transported without being disarranged and wrinkled. Heretofore, there have been provided in such bags, garment supporting frames adapted to maintain garments in an orderly condition during transportation. But such frames have been objectionable in that they are inconvenient to manipulate; and in many instances, appreciably increase the weight of the bag.

It is, therefore, an object of this invention to provide in a traveling bag a garment supporting device which can be conveniently and readily positioned to properly receive clothing.

A further object is the provision of a garment supporting device adapted to accommodate a plurality of garment hangers, and having means to prevent such hangers from being removed or falling from said device when the latter is in a folded condition.

A further object is the provision in a traveling bag of a garment supporting frame pivotally mounted in the cover of the bag and having extensions adapted to be supported by the main body of the bag to provide a stable structure when it is desired to place garments thereon.

These and other objects are attained by the novel construction, combination and arrangement of parts hereinafter described and shown in the accompanying drawings, constituting a material part of this disclosure, and in which:

Fig. 1 is a perspective view of a traveling bag in an open condition with the garment supporting device in an extended position.

Fig. 2 is a perspective view showing the garment supporting device in a folded condition in the cover of the traveling bag.

Fig. 3 is a perspective view of an element of device in an extended condition.

Fig. 4 is a perspective view of the element shown in Fig. 3 is a folded condition.

Fig. 5 is a perspective view of elements for supporting the garment supporting device when in an extended position as shown in Fig. 1.

Referring to the drawings, in Fig. 1 is shown a traveling bag of the wardrobe type having a

cover 1 hingedly connected to a main body portion 2. Attached to side walls 3 of the cover 1, and adjacent the side of the cover remote from the hinge connection with the main body 2, are brackets 4, to which are pivotally connected flat bars 5, the opposite ends of which are pivotally connected to similar flat bars 6, the latter being connected near their free ends by a cross bar 7. Projecting laterally from the free ends of bars 6, are pins 8, which are adapted to enter notches in metal U-shaped members 9 attached to the inner side walls of the main body 2 of the traveling bag. As will be seen in Fig. 1, the structure above described provides a frame which is supported by the members 9 on the main body 2 and by the brackets 4 on the side walls of the cover 1.

Adjacent the pivotal connection of bars 5 and 6 and extending between the two bars 6 is a rod 10 having right-angularly directed portions 11, which are rigidly secured to the bars 6 by members 12 which are preferably riveted to the bars 6. Positioned below the rod 10, and mounted on the bars 6 are U-shaped rods 13, each having a leg 14 secured to a bar 6, and a leg 15, supported by a brace 28 secured to a bar 6. See Fig. 3. Pivotally connected to each of the legs 15 are rods 17 having upturned portions provided with heads 18 which in turn are provided with recesses 19 adapted to receive the rod 10 frictionally when the rods 17 are folded to a position parallel with the rod 10 as shown in Fig. 4.

As shown in Figs. 3 and 4, the legs 15 of the U-shaped member 13, are adapted to support one or more garment hangers 20, which have enlarged portions 21 at their ends, and slots to receive the legs 15. When it is desired to mount one or more hangers 20 on the legs 15, the rods 17 are moved to an extended position as shown in Fig. 3. The hangers 20 are then placed on the rods 17 and slid back on to the legs 15, after which the rods 17 are folded to the position shown in Fig. 4. When the hangers 20 are on the legs 15, they can not be removed as upward movement of the hangers is prevented by projections 22 at the ends of the hangers, which projections engage the legs 14 to prevent upward movement of the hangers; and forward movement of the hangers is limited by the folded rods 17.

Projecting laterally from the bars 6 and intermediate the length thereof are pins 23, which are adapted to enter openings 24 in latching elements 25 mounted on the side walls 3 of the cover 1. The latching elements are provided with buttons 26 for releasing the pins 23 when desired. The

latching elements 25 are of a well known and old type, and the structure thereof is not herein described in detail.

In operation, when it is desired to fold the garment supporting device into the cover as shown in Fig. 2, the bars 6 are raised to disengage the pins 8 from the notches in the members 9, after which the bars 6 are brought forward and upwardly so that the pivotal connections between bars 5 and 6 will move downwardly. The bars 6 are then moved into the cover 1, with the free ends of the bars 6 directed upward; and the pins 23 projecting from bars 6 are caused to enter the openings 24 in the latching elements 25.

15 The hangers 20 and the garments thereon will then be positioned in the cover 1, with portions of the garments folded over the cross-bar 7. Obviously, by means of my garment supporting device, garments can be transported without disarrangement or wrinkling; and the supporting device can be conveniently and readily manipulated to place it in an extended position as shown in Fig. 1 for the purpose of removing garments therefrom.

The foregoing disclosure is to be regarded as descriptive and illustrative only, and not as restrictive or limitative of the invention, of which obviously an embodiment may be constructed including modifications without departing from the general scope herein indicated and denoted in 30 the appended claims.

Having thus described my invention, what I claim as new and desire to secure by Letters Patent, is:

1. In a garment supporting device a pair of 35 bars, means to support said bars in an upright

position, U-shaped members attached horizontally to said bars, the inner legs of said members being adapted to support garment hangers, extension rods hingedly connected to the inner legs of said members, a cross-rod connected to said pair of bars, garment hangers having means to cooperate with the outer legs of the U-shaped members to prevent upward removal of the hangers, and means at the free ends of said extension rods engageable with said cross-rod to prevent removal 10 of garment hangers from said legs. 5

2. In a garment supporting device, a pair of bars, U-shaped members attached horizontally to said bars, the inner legs of said members being adapted to support garment hangers, members 15 hingedly connected to the inner legs of said U-shaped members, a cross-rod connected to said pair of bars, garment hangers having means to cooperate with the outer legs of the U-shaped members to prevent upward removal of the 20 hangers, and latch means carried by said hingedly connected members, said latch means being engageable with said cross-rod to prevent removal of garment hangers from said legs.

3. In a garment supporting device, a pair of 25 bars, U-shaped members attached horizontally to said bars, the inner legs of said members being adapted to support garment hangers, a cross-rod connected to said pair of bars, garment hangers having means to cooperate with the outer legs of 30 the U-shaped members to prevent upward removal of the hangers, and means carried by said inner legs engageable with said cross-rod to prevent removal of garment hangers from said legs.

ABRAHAM LEVINE. 35
